(57) **CLAIM**

I claim the ornamental design for sterilizing and disinfecting apparatus, as shown and described.

DESCRIPTION

FIG. 1 is a right side perspective view of the sterilizing and disinfecting apparatus of the claimed design.

FIG. 2 is a front elevational view of the claimed design.

FIG. 3 is a right side elevational view of the claimed design.

FIG. 4 is a left side elevational view of the claimed design.

FIG. 5 is a top view of the claimed design.

FIG. 6 is a rear elevational view of the claimed design; and, FIG. 7 is a bottom view of the claimed design.

The broken lines shown in the drawings illustrate portions of the sterilizing and disinfecting apparatus that form no part of the claimed design.
